C. E. BETCHER.
SMOKE AND GAS BURNING FIREBOX.
APPLICATION FILED AUG. 21, 1918.

Patented Apr. 5, 1921.

UNITED STATES PATENT OFFICE.

CHESTER E. BETCHER, OF MINNEAPOLIS, MINNESOTA.

SMOKE AND GAS BURNING FIREBOX.

1,373,478.

Specification of Letters Patent.

Patented Apr. 5, 1921.

Application filed August 21, 1918. Serial No. 250,774.

To all whom it may concern:

Be it known that I, CHESTER E. BETCHER, a citizen of the United States, residing at Minneapolis, in the county of Hennepin and 5 State of Minnesota, have invented certain new and useful Improvements in Smoke and Gas Burning Fireboxes, of which the following is a specification.

My invention relates to smoke and gas 10 burning fire boxes for furnaces. An object of my invention is to provide means for securing more perfect combustion of fuel than is possible in furnaces which are now in common use, whether combustion is supported by air alone or by both air and 15 steam. In customary furnaces which are in use, only an imperfect combustion of the fuel is obtained because a large percentage of the gaseous products pass off unconsumed. The result of this is that a large 20 amount of potential heat is wasted and quantities of smoke and soot are discharged into the atmosphere with attendant injurious results. In carrying out my invention, 25 I provide the fire-box with means which cause the smoke and gases coming from the fuel to be subjected to a high degree of heat before they are given an opportunity to escape through the chimney. I also provide 30 means for preheating the air which is supplied to support the combustion of the gases and smoke. By the provision of these means, I secure a steady and uniform heat and almost complete combustion of the 35 combustible elements. This results in a great saving of fuel and elimination of smoke.

The full objects and advantages of my invention will appear in connection with the detailed description thereof, and the novel 40 features embodied in my invention are particularly pointed out in the claims.

The accompanying drawings illustrate my invention applied to a boiler furnace, but it is to be understood that the invention is not 45 limited to this type of furnace and may be employed to advantage in other types of furnaces.

Referring to the drawings which show my invention in one of the embodiments which 50 it may assume, Figure 1 is a longitudinal section of a boiler furnace with my invention applied thereto. Fig. 2 is a view in cross section. Fig. 3 is a view on the line 3-3 of Fig. 2 looking downwardly.

55 In the drawings, 10 designates a boiler which may be of the usual construction set

in brick work 11 constituting the main walls of the furnace and having a stack 12. Underneath the rear portion of the boiler is a combustion chamber 14 and underneath the 60 front portion of the boiler is a fire-box 16. The front of the fire-box is provided with a charging door 18 and at the bottom there is a grate 20 discharging into the main ash pit 22 in the usual manner. The grate is 65 operated by a hand lever 21 and a connecting rod 23. Extending downwardly at the rear end of the grate 20 is a transverse partition 24 which extends about half-way to the bottom of the main ash pit. Above the 70 rear end of the grate and spaced from the bottom of the fire-box is a wall member 26 which forms an essential feature of my invention. This wall member is preferably 75 molded in one piece from a mixture consisting of substantially the following parts by measure: two parts of crushed burnt fire brick, one part of fresh fire clay, and one part of saw-dust. This mixture has no shrinkage during firing. This wall member 80 is molded into shape so that the rear portion thereof is curved to fit closely upon the boiler and leave no communication at this place between the fire-box and the combustion chamber. The front of the wall member 85 is of less height than the rear portion so as to be spaced from the boiler and said member is provided with a plurality of flues 30 which extend downwardly from the top of the short portion and near the bottom of 90 the wall are preferably turned rearwardly at 32 so as to discharge behind the wall member. For large furnaces, this member may be molded directly into its place in the furnace and fired and burned therein. On 95 account of the non-shrinking character of the composition, the said member remains securely supported in place. For smaller furnaces, the member may be molded outside of the furnace in one or more pieces 100 and then placed in position in the furnace where it is supported by the brick walls. The saw-dust soon burns out, leaving a porous structure which readily becomes highly heated. The gases and smoke in the fire-box 105 pass through the flues and during their passage are heated to a high temperature. The tops of the flues 30 are provided with slides 34 which may be pushed over the flues to partly close them when the full draft is not 110 required. If desired, a small door 35 may be provided at the front of the furnace so

that the slides may be readily reached. The wall or flue member 26 is spaced at its lower end a short distance from the front of the bridge wall 36 which is inclined upwardly 5 at 38 away from the member 26. The top 40 of the bridge wall is curved and spaced a short distance from the boiler so as to leave a passage 42 leading into the combustion chamber 14. At the rear of the grate 20 is 10 a secondary grate 44 and underneath this grate is an auxiliary ash-pit separated from the main ash-pit by the partition 24. The grate 44 is operated by a hand lever 45 and a connecting rod 47. The bottom of the 15 auxiliary ash-pit consists of a pivoted plate 46, the rear end of which is weighted so that the plate is normally held in horizontal position with its rear end resting upon the stop 48 and its front end abutting the partition 24. 20 The front of the plate is provided with an arm to which is pivoted a rod 50 extending to the front of the furnace by means of which the contents of the auxiliary ash-pit may be dumped into the main ash-pit. A passageway 25 or draft flue 52 leads from the outside of the furnace through bridge wall into the auxiliary ash-pit, a damper 54 being provided to regulate the draft through the passageway. The bottom plate 46 closes the 30 auxiliary ash-pit and causes the current of pre-heated air to pass up through the secondary grate to the rear of the wall member 26 so that the gases of combustion are discharged directly into said current. The bottom plate also prevents cold air from the 35 front of the furnace passing through the auxiliary ash-pit, which undesirable result would otherwise occur. The fresh air which is supplied through the passageway 52 is 40 pre-heated by the hot walls of the furnace and then mingles with the hot gases and smoke which are compelled to pass through the flues 30, thus furnishing the oxygen necessary to support combustion. Very 45 satisfactory results are obtained in this way. Sometimes, however, it may be desirable to mix steam with the heated gases and for this purpose I have shown a steam pipe 56 which discharges near the exit end of the 50 flues. The position of the end of the pipe 56

is indicated in dotted lines in Fig. 1. In order that the condition of the furnace may be readily observed, I may provide a tube 58 containing a transparent disk of mica or glass.

55

The operation and advantages of my invention will be obvious from the foregoing description. Practically all of the gases which are formed in the fire-box are forced to pass through the highly heated flues 30 60 and these very hot gases as they escape from the discharge end of the flues are mixed with preheated fresh air which causes almost complete combustion of the gases to occur. This results in saving a large percentage of the fuel and prevents the discharge of smoke 65 from the chimney or stack. The provision of a non-shrinking flue member molded in place in the fire-box results in said member being very securely held in place without 70 danger of its falling down into the fire-box.

I claim:

1. A furnace comprising a fire-box, a wall member dividing said fire-box into front and rear compartments, said wall member being 75 spaced above the bottom of the fire-box and provided with flues leading from said front compartment to said rear compartment, a main ash-pit below said front compartment, an auxiliary ash-pit below said rear compartment and means for supplying pre-heated air to said auxiliary ash-pit.

2. A furnace comprising a fire-box, front and rear grates in the bottom of said fire-box, a wall member dividing said fire-box 85 into front and rear compartments, said wall member being spaced above the line of separation of said grates and provided with flues leading from said front compartment to said rear compartment, a main ash pit below the front grate, an auxiliary ashpit below the rear grate, means for supplying preheated air to said auxiliary ashpit, a pivoted plate constituting the bottom of said auxiliary ashpit, and means whereby said plate may 90 be tilted to discharge the contents of said auxiliary ashpit into said main ashpit.

In testimony whereof I hereunto affix my signature.

CHESTER E. BETCHER.
